UNITED STATES PATENT OFFICE.

ERICH BAUM, OF NUEREMBERG, GERMANY, ASSIGNEE, BY MESNE ASSIGNMENTS, TO THE CHEMICAL FOUNDATION, INC., A CORPORATION OF DELAWARE.

CLEANSING COMPOUND AND PROCESS OF MAKING SAME.

1,340,315.

Specification of Letters Patent.

Patented May 18, 1920.

No Drawing.

Application filed November 28, 1913. Serial No. 803,877.

To all whom it may concern:

Be it known that I, Dr. ERICH BAUM, a subject of the Emperor of Germany, and a resident of Nuremberg, in the Empire of 5. Germany, have invented certain new and useful Improvements in Cleansing Compounds and Processes of Making the Same, of which the following is a specification.

The object of my invention is to provide 10 a non-inflammable cleansing compound containing trichlorethylene in the form of a solution and to this end I may prepare said solutions in the preferred manner herein-after described.

15 Trichlorethylene is a well known agent for dissolving grease and may therefore be used for cleansing fabrics by dissolving therefrom grease and other impurities more or less closely related thereto. It is, however, not advisable to use trichlorethylene in 20 its concentrated form but it is desirable to bring it into a diluted form in order to have a good and economical effect.

I have found that this purpose may conveniently be achieved by embodying the trichlorethylene in a neutral soap solution and have furthermore found it advisable to mix therewith another hydrocarbon, especially a liquid mineral hydrocarbon, as for 30 instance kerosene. The term "kerosene" as used by me refers to that kind of mineral oil which is sold generally as a burning oil under such trade-names as "kerosene," "Solar oil," etc., the term "petroleum" being 35 used in some places, particularly in continental Europe, to designate such oils, the specific gravity of which, although varying according to regulations by the Governments of various countries, is usually about 40 0.825 to 0.83, the boiling point ranging from about 175° C. to 260° C. I prefer to add the kerosene and trichlorethylene to the soap solution in the form of a mixture.

To produce my new compound I may proceed as described in the following example:

I heat 11.5 kilos of ricinoleic acid in a suitable vessel up to about 50° C. and add thereto a solution of 20 Bé. specific gravity, containing the theoretical quantity of 50 caustic alkali, the whole being gently stirred. By this a clear gelatinous soap is soon obtained. A mixture of 12.5 kilos trichlorethylene and 750 grs. kerosene is then permitted to gradually flow into same, the latter ingredients being readily dissolved in

the soap. To the mass thus obtained water is added until a volume of 100 liters is reached. For equalizing a slight variation in color, as may be shown by the various charges, a little coloring matter may be 60 added.

The solution of trichlorethylene in a solution the chief ingredient of which is soap, is a very advantageous form for use since it may be readily, safely and economically applied to clothing and the like, for cleansing the same.

It is understood that where I say that I use ricinoleic acid for the soap employed in the compound, I can just as well use soap 70 made by direct saponification of castor oil, and that any other suitable soap made by direct saponification of raw material of either vegetable or animal origin or soaps made from acids derived from such raw materials 75 may serve as a substitute of the ricinoleic acid mentioned in above example, provided said soap does not contain sulfur in any form especially in the form of the so-called "sulfo-group" which is present in soap made 80 from sulfonates obtained by treating suitable oils with sulfuric acid.

I do not restrict myself to any of the proportions stated or ingredients named further than the scope of the appended claims demands.

What I claim and desire to secure by Letters Patent is:—

1. A cleansing compound consisting of a solution containing a neutral soap, trichlor- 90 ethylene and kerosene.

2. A cleansing compound consisting of a solution of a neutral soap, trichlorethylene, kerosene and water.

3. The process of making a cleansing com- 95 pound in the form of a solution containing a neutral soap, trichlorethylene and kerosene consisting in dissolving trichlorethylene in the presence of kerosene in a neutral soap solution.

4. The process of making a cleansing com- 100 pound in the form of a solution containing a neutral soap, trichlorethylene and kerosene consisting in dissolving a mixture of trichlorethylene and kerosene in a neutral 105 soap solution.

ERICH BAUM.
